ALBERT H. EMERY, OF STAMFORD, CONNECTICUT.

PROCESS OF CONSTRUCTING AND ASSEMBLING PARTS OF GUNS.

SPECIFICATION forming part of Letters Patent No. 727,767, dated May 12, 1903.

Application filed April 6, 1900. Serial No. 11,904. (No model.)

To all whom it may concern:

Be it known that I, ALBERT H. EMERY, a citizen of the United States, residing at Stamford, in the county of Fairfield and State of Connecticut have invented certain new and useful Improvements in Processes of Constructing and Assembling the Parts of Guns, of which the following is a specification.

The nature of my invention relates to the assembling of that class of heavy ordnance which consists of a plurality of concentric tubes or jackets and to the construction and assembling and disassembling of chamber and bore linings. Several different examples of construction are shown in the accompanying drawings to illustrate and clearly explain this process in detail.

In said drawings, Figure I is a side elevation of a completed gun, one-half of which is shown in section. Figs. II, III, IV, V, VI, VII, and VIII show details of this gun and modifications thereof on larger scales, all in section. Figs. IX, X, XI, and XII show portions of the gun in section, with some parts of the apparatus in section, and the method of assembling the parts of the gun.

The gun shown in Fig. I consists of a barrel 1, jacket 2, banding hoop or tube 3, trunnion-band 4, lining 5, breech-block 6, breech-sleeve 7, banding-rings 8 and 9, and breeching 10. In Fig. II the barrel 1 is not only provided with bore-lining 5, but there is provided also a chamber-lining 11, while in Fig. III there are shown the bore-lining 5 and chamber-lining 11 with an additional bore-lining 12 in front of the bore-lining 5 and a lining 13 exterior to the linings 5 and 12 in front of the chamber-lining 11. The parts 2 and 3 may each be made of a single piece, as here shown, or they may be compounded of several pieces. They are best made of fluid-pressed steel forged hollow, oil-tempered, and annealed sufficiently to give the required ductility and then strained either separately or together by fluid or liquid pressure acting from the interior outward. The barrel 1 is also preferably made of forged fluid-pressed steel oil-tempered and, if necessary, annealed to the extent required to give it sufficient ductility to be strained, as desired. It may be strained by the liquid acting on the interior, giving a permanent strain of com-

pression to the interior and tension to the exterior before it is assembled with the jacket 2, and then finished on its exterior and assembled with the jacket 2, as hereinafter described, or it may be assembled with the jacket 2 either before or after this jacket has been strained and then stretched out by liquid or fluid pressure acting on its interior until it is firmly seized by the jacket and sufficiently extended to give the required relative strain of tension in the jacket and compression in the barrel after the removal of the liquid-pressure, and these two parts then are finished on the exterior and the interior, the jacket 2 ready to receive the hoop 3 and the tube 1 ready to receive the lining 5, Fig. 1, or the linings 11 and 5, Fig. II, or 13, 12, 11, and 5, Fig. III, according to the number of these linings used.

A very good way of making this gun is to bore and turn the hoop 3 with smaller diameters than it is to have in the finished gun, then stretch it with internal pressure very considerably, causing resultant strains of tension on its exterior and compression on its interior when the fluid-pressure is removed. The trunnion-band 4 and securing and strengthening ring 8 may be placed loosely on the hoop 3 and are tightened in position by the stretching of the hoop, as explained, and are still further tightened when the finished hoop 3 is subsequently put under heavy strains of tension throughout by being assembled with the jacket 2 and barrel 1, as hereinafter described.

The jacket 2 should be made with external and internal diameters less than it is to have in the finished gun and then expanded, as described, and assembled with the barrel 1 fitting loosely therein, or it may be assembled with the barrel 1 before it has been strained, but is preferably strained first to have nearly or quite its finished diameters, and then the barrel 1 inserted loosely and strained with internal pressure sufficient to cause the jacket 2 to tightly seize it and hold it under a permanent strain of compression. The jacket 2 should then be finished on its exterior, when it is ready to be assembled with the hoop 3, and then may be assembled as illustrated in Fig. XII.

14 and 15 (see Figs. I, II, III, and IV) are

small ducts used to introduce liquid under pressure when the parts are being assembled or disassembled in the operation of assembling or lining or relining a gun.

17, Fig. XII, is a supporting-beam of the straining and assembling machine, which supports and fixes one end of the work in position, the work resting at one end in the supporting-collar 18 (shown in Fig. XII), and at the other end on a supporting-beam of the machine. (Not here shown.) The jacket 2 is provided with an extension-tube 19, Fig. XII, with a joint between it and the tube closely sealed by the packing 20, which may be constructed in any suitable manner to withstand the high pressure required in assembling the parts. 21 and 22 are packings at the extremities of the hoop or tube 3, which close the joints between it and the interior parts.

24 is a pipe bringing liquid under heavy pressure through a small duct 25, Fig. XII, into the annular space between the tube 3 and the interior parts.

26 is a portion of the front end of the piston-rod of a heavy hydraulic press carrying the collar 27, which centers and supports the extension-tube 19 and forces it firmly against the packing 20 and jacket 2 during the process of assembling. To avoid making this tube 19 very long, the tube or hoop 3 and jacket 2 are provided with offsets, so that while the inner diameters of 3 are smaller than the corresponding outer diameters of the jacket 2 it may still be slipped nearly to its seat before introducing the pressure liquid into the space between them. The front end of the gun is supported by the straining and assembling machine and operated on by a hydraulic press therein, being forced to the left thereby, carrying with it the jacket 2, extension-tube 19, collar 27, and piston-rod 26, as the whole of these interior parts move along until the hoop 3 has reached its permanent seat on the jacket 2, the pressure of the press at the right-hand end being superior to that of the press at the other end of which the piston-rod 26 is shown; but this latter pressure must be sufficient to keep a closed joint at the packing 20. When the hoop 3 has reached its seat, the pressure on the liquid may be removed and the liquid allowed to flow out when the parts 2 and 3 are tightly seized together by the contraction of the hoop 3 and expansion of the jacket 2. To allow of more ready introduction and removal of the liquid, a small spiral groove may be made on the interior of the hoop 3, reaching from the duct 25 to a point at or near the packing 22. This groove is shown in Fig. XII much enlarged to make it appear in the small-scale drawing shown. After the parts 1, 2, and 3 are assembled and properly strained the exterior of the gun may be finished and the interior bored to receive the lining 5, or such additional linings as are to be inserted. The method of inserting the bore-lining 5 where it alone is used is illustrated in Fig. IX, where

1, 2, and 3 represent the tube, jacket, and hoop of the gun, and 5 the lining to be inserted. This lining may be inserted before the gun has been rifled or before it and the lining have been finally bored and rifled; but I prefer to finish the bore of the gun as far as from the front end to the lining-tube and to rifle it before inserting the lining-tube 5, in which case this tube should also be finished and rifled, care being taken that its exterior and interior diameters are so made that when compressed and forced to its position in the gun it will have the desired size of the bore. This lining-tube should be of very hard elastic highly-worked steel and preferably inserted with such diameters that when in its seat in its normal state the compression is so great that extending the walls of the gun by the pressure of the gases in firing it will not wholly remove this strain of compression even at the time of firing. This is most conveniently accomplished by making the exterior of this bore-lining slightly conical or with small offsets, as shown in Fig. IX, where three such offsets are provided. The lining-tube is slipped in until the shoulders at the small offsets on the two pieces reach or nearly reach each other. To the rear end of this lining 95 is screwed the assembling-head 28, which is secured to the piston-rod 26, as shown in Fig. IX. A convenient way of attaching the assembling-head to the lining is to screw the parts together, as shown in Figs. IX and XI. Around the assembling-head 28 is a packing 29 to confine the liquid at this point and prevent its flowing away between the head and the gun-barrel 1. To prevent the liquid flowing between this packing and the rear of the lining-tube 5, a band 30, preferably made of bronze or copper, is secured to the rear of the lining-tube 5 by a metallic packing 31. The ring or band 30 reaches back over a portion of the packing 29, covering the joint between it and the lining-tube to prevent the flow of liquid. Should any liquid leak through this joint, it can pass away through the duct 28^a, (shown in the assembling-head 28 in Fig. XI.) The packing 29 consists of a screw-collar 32, screwed onto the assembling-head and provided with a sleeve which seats at its conical end. This sleeve is provided on its interior with a series of small grooves 33 to reduce the surface of pressure and prevent leaking at that point. The annular space between the screw-collar 32 and the assembling-head 28, on which it is screwed, contains the other parts of the packing, which consist of a conical collar 34, with a thin lip 35 extending back from its rear, a flexible packing 36, and a fibrous elastic packing 37, which is forced forward and outward by the ring 38 against the packing 36 and collar 34 with its lip 35 when the screw-collar 32 is screwed to its seat. The rings 34 and 38 may advisably be made of hard bronze. 34 should be well hammered before finishing, but may, if preferred, be made of highly-elast.

tie steel. The part 36 may be made of leather, and the elastic packing 37 may be made of a fine hemp-cord. Packings 21 and 22, previously mentioned, may advisably be made and 5 applied similarly to the packing 29. Packings 39, 40, and 41 (shown in Figs. V, VI, and VII) are entirely similar to the packing 29 described, and corresponding parts are given similar numbers.

10 In Fig. IX the assembling-head 28 is shown with an extension piece or bar 42, carrying a rifled head 43, which fits in the rifled grooves of the bore-lining 5 and the rifled grooves in the finished part of the barrel 1. 41 is a packing 15 at the front end of the lining-tube 5, which is shown on an enlarged scale in Fig. VII. The bore-lining has a thin lip or flange 5^a at its front, extending beyond the packing 41, which will cover the joint between the packing 20 and barrel of the gun when the lining has been slipped to its seat, as shown in Fig. VII. This extending lip is surrounded by small shallow grooves 44, as shown in Fig. VII, to reduce the surface of pressure between it and 25 the gun-barrel 1 for the purpose of preventing the leakage of gas through the joint. These grooves may be in the gun-barrel 1, as shown, or they may be on the lip 5^a of the lining 5, if preferred. When the parts are 30 ready to be assembled in the position shown in Fig. IX, liquid or gas is brought under heavy pressure through the duct 14 into the space between the surfaces of the lining-tube 5 and the parts surrounding it. This pressure 35 must be sufficient to reduce the diameter of the tube 5 sufficiently to allow it to be pressed forward to its seat. As it moves forward under the action of the piston-rod 26 the rifled head 43 necessarily rotates with the 40 grooves in the gun-barrel 1, carrying the lining-tube 5 with it in its rotation until the latter meets the gun-barrel 1 at its front end, at which time the rifling in the lining-tube 5 will match the rifling in the gun-barrel 1. 45 The head 43 must be loose on the bar 42 as regards rotation, so that the assembling-head 28 can be unscrewed from the lining-tube 5 without rotating the rifled head 43. The dotted line at 45 in Fig. IX shows the reduced 50 diameter of the bar 42 passing through the rifled head 43, which while turning loosely on the bar 42 may or may not be secured to it, as desired. In forcing liquid through the duct 14 provision must be made to prevent 55 its passing between the surfaces of the members 2 and 3 or 1 and 2, which may be accomplished by using a lining-tube 46, secured in position by the screw-tube 47, which seals the joints at its two extremities. Before the gun 60 is finished the tube 47 is removed and a short screw firmly seated in its place, making a joint between its conical end and that of 46 and sealing also the joint at the inner end of the tube 46. This screw should have the duct 65 14 continued through it for the purpose of allowing any gases which leak into the joint between the rear of the lining-tube 5 and the

gun-barrel 1 to escape. The duct is shown in dotted lines in Fig. 1 in the finished gun.

Fig. X shows a section of a portion of the 70 rear of the gun and the chamber-lining 11 being inserted into the gun-barrel 1. This lining is provided with small offsets, one at the duct 14 and one at a point close to the rear of the gun-barrel 1. The outer diameters of the different parts of the lining are 75 larger than the corresponding diameters of the gun-barrel in which it seats; but the parts are constructed with offsets at the different diameters somewhat larger than the 80 diametrical compression which the lining-piece requires for its insertion. This permits of this lining-piece being slipped at once loosely nearly to its seat, as shown, when the small shoulders striking against each other 85 arrest its progress. To retain the liquid-pressure throughout its whole extent, so as to reduce its diameter for complete insertion, an extension member or tube 48 is screwed into the jacket 2 and is provided with a packing 49 90 to close the joint between it and the gun-barrel 1. Instead of the screw-thread holding this member in position it will often be convenient to hold it by direct pressure, as illustrated in Fig. XII. Around the assembling- 95 head 28 is a packing 29, similar to that shown in Fig. XI. At the front of the lining 11, Fig. X, a packing 50, which is similar to packing 41 in Fig. VII, is used. Should there be another lining, however, in front of the lining-tube 11, as shown in Fig. III, where a lining 13 is previously placed, then the packing 50 will be slightly modified and will be like packing 40, (shown in Fig. VI,) where the screw-collar 32 is recessed for the overlapping band 30, which is used in making a joint between the lining 13 and the assembling-head when introducing 13 to its seat.

It often happens in assembling parts of 110 guns by this method that the assembling-thread 51 (shown at the rear of the lining members in Figs. V, VI, and VIII to connect them to the assembling-head in assembling or disassembling the parts of the gun) is not provided. In Fig. X no assembling- 115 threads are shown at the rear of the lining 11. In this case and similar ones the assembling-head 28 may have a long cylindrical lip or tube 52, extending into the lining-tube 11 and may fit loosely therein before the lining 120 is compressed by the pressure of the liquid or fluid on its exterior. The joint between the packing 29 and the rear of the lining 11 is covered by a packing plate or band 30, as before mentioned. When liquid is forced 125 under heavy pressure through the duct 14, the lining-tube 11 will be reduced in diameter sufficiently to allow of its being forced forward to its seat. Its diameter at the rear and the exterior diameter of the part 52 should 130 be constructed of such sizes that when so reduced by this liquid-pressure the part 52 will be firmly seized by the pressure of the lining-tube upon it, binding these parts

firmly together with pressure sufficient to allow of the tube being inserted or extracted by the assembling-head 28, which is operated by the piston-rod 26. Should any leak pass the joint between the packing 29 and the rear of the lining-tube 11, the fluid or liquid leaking through should pass off without much pressure through the small duct 31. Where assembling-threads 51 are used at the rear of the lining-piece, as shown in Figs. V, VI, and VIII, it is sometimes necessary to fill them to better support the lip of the piece, which is inserted interior thereto. In case this occurs between two bore-linings, as in the illustration in Fig. VI, these threads should be filled by another piece 53, made of brass or bronze or other suitable metal and placed in position, as shown in Fig. VI. If the joint is one between two lining members 11 and 13 at a place not next to the bore, these threads may be left open, as shown in Fig. V, where the filler 53 is dispensed with. The assembling-threads when used at the rear of the lining-tube 5, as shown in Fig. VIII, are filled by a lining-piece 54, which extends back to the chamber of the gun and has provided on its interior a seat or seats slightly conical, into which is forced by heavy pressure the filling and finishing piece 55, which expands the sleeve 54 and rear of the lining-tube 5 to position and covers the joint between them. To prevent the flow of gases around these pieces, their exteriors may be provided with small grooves 56. (Shown in Fig. VIII.) The filler 54 may be made of soft steel or of hard bronze. The filler 55 should be made of hard bronze or, better, of highly-elastic tempered steel and with such a diameter or diameters on its exterior that when assembled in its proper place in the gun it will be subject to a strain of compression sufficient to remain under compression when the gun is expanded under the pressure of the gases produced by the maximum charges allowed to be fired therein. Should there be leaks of the gases by these parts, they will pass out through the duct 14 and give notice of the leakage, which should not be permitted to any great extent. If necessary, these parts 54 and 55 may be removed and new ones substituted therefor to prevent the leakage.

For the better expulsion of all the liquid between the bearing-surfaces of parts which are assembled by the process described it will be best in general to provide on the exterior of the part which is inserted or on the interior of the part which is slipped over another the small spiral groove, as illustrated in Figs. IV, X, and XII. This groove will generally be placed on the member which is provided with a packing or packings to be used in assembling the piece. The rear of the lining-tube 5 may be finished and supplemented by parts 54 and 55, as shown in Fig. VIII, or it may be finished simply as shown in Fig. IV, where these pieces are dispensed with, and the rear of the member is provided with a

series of small shallow grooves 57 to prevent the flow of gas between it and the adjoining member of the gun. Should there be leakage 70 at this point, the gases will pass out through the duct 14 and give notice of the leak.

58 shows the small spiral groove around the lining member 5.

Having thus described my invention, the 75 following is what I claim as new therein and desire to secure by Letters Patent:

1. The process of constructing and assembling parts of a gun, which consists of forming a lining or inner member with an external 80 diameter larger than the internal diameter of the part in which it is to be seated, temporarily reducing the diameter of the said inner member by means of a thin film of fluid forced by heavy pressure between it and a 85 surrounding body, and while so reduced forcing the inner member home to its seat; substantially as described.

2. The process of assembling parts of a gun which consists in forcing a thin film of fluid 90 under heavy pressure between a lining or internal member of a gun and a body surrounding the same, thus temporarily reducing the diameter of the said internal member relatively to that in which it is to fit, and while 95 so reduced slipping the said internal member into its seat; substantially as explained.

3. The process of assembling parts of guns which consists in forcing a thin film of fluid 100 under heavy pressure between the inner surface of an external member and an internal body supporting said pressure, thus expanding the diameter of the said outer member and then forcing the said outer member to its seat on the inner member while thus expanded, as explained.

4. The process of constructing and assembling guns or the parts thereof, which consists in constructing one part which is to fit in another slightly conical or with one or more offsets, the part which is to be interior to the other having diameters somewhat larger than the corresponding inner diameters of the part in which it is to be seated, then slipping the parts one within the other until stopped 115 by the enlarged diameter of the inner part, then reducing the diameter of the inner part relatively to that of the outer by means of a thin film of fluid forced into the space between the inner part and the surrounding 120 body by which the pressure is sustained, slipping the inner member to its seat while thus reduced in diameter, and then removing the fluid-pressure and allowing the outer part to contract and the inner part to expand, and 125 firmly seat or fit the parts together; substantially as set forth.

5. The process of assembling parts of guns, which consists in applying an extension-piece of suitable diameter to an inner member upon 130 which an outer member is to be assembled with a tight joint between them, slipping the outer member over said extension-piece, forcing fluid under heavy pressure into the inter-

vening space so as to expand the said outer member and slipping the latter to its seat while thus expanded; substantially as explained.

5 6. The process of assembling parts of guns, which consists in applying an extension-piece of suitable internal diameter to the end of a member of a gun within which a lining or other internal member is to be assembled, 10 slipping the inner member within the extension-piece, forcing fluid under heavy pressure into the intervening space, so as to reduce the diameter of said inner member and slipping the latter to its seat while thus reduced in diameter, as explained.

15 7. The process of assembling or disassembling two or more parts of a gun, which consists in introducing liquid-pressure, sufficient to increase the diameter of the external part 20 and decrease the diameter of the internal part, and allow the parts to be moved to the desired relative position; one of these parts being provided on its seating - face with a spiral groove to facilitate the introduction 25 and removal of the liquid used in carrying out the process.

8. The process of construction and assembling of guns which consists in passing liquid under heavy pressure through a small duct 30 leading through the exterior member to the adjoining surfaces of the members to be assembled, sufficient to reduce the diameter of the interior member, and increase that of the exterior member, and allow the inner member 35 to be slipped to its seat therein, or if in its seat, to be slipped out.

9. The process of construction and assembling of guns, which consists in constructing a closed chamber between the member to be 40 slipped over another, and a part interior thereto, by providing a suitable packing at or near each end of said member, then forcing the liquid or fluid between the adjoining surfaces with sufficient pressure to separate 45 them and allow the members to be slipped or forced together to their relative positions, in the finished gun.

10. The process of inserting or withdrawing the lining or other part of a gun, which consists in inserting within it an assembling 50 bar or head 28, provided with a long projecting lip or tube 52 extending a considerable distance into and fitting the member to be assembled or disassembled with a packing between said member and the assembling-head, 55 then applying fluid - pressure between said member and the surrounding part, sufficient to reduce its diameter and permit of its being inserted into or removed from its seat and sufficiently also to cause it to seize firmly the 60 lip or tube of the assembling-head, and then moving said part to or from its seat.

11. The process of assembling the rifled bore-lining 5, with the rifled gun-barrel 1, which consists in inserting within the rifled 65 bore-lining the bar 42, connected to the assembling-head 28 and carrying a rifled part 43, extending through the bore-lining 5, into the gun-barrel 1, and provided with grooves and lands closely fitting the grooves and lands 70 in the lining 5, and the gun-barrel 1, then introducing fluid-pressure between the lining 5, and surrounding parts, sufficient to reduce its diameter to the extent necessary to permit its movement, and then forcing it to its 75 seat, when the grooves in the lining will be in line with and match those in the gun-barrel.

12. The process of assembling or disassembling an outer and an inner member of a gun which consists in constructing said outer and 80 inner members with offsets or changes in diameter in their adjoining surfaces, permitting said parts to move one within the other for a part of the way, providing one of said members with a duct extending through it at or 85 near such an offset or change in diameter, then introducing through said duct fluid-pressure sufficient to reduce the diameter of the inner member to the extent which permits its movement to or from its seat.
